(57) CLAIM

The ornamental design for a jewelry item, as shown and described.

DESCRIPTION

FIG. 1 is a front perspective view of a jewelry item showing my new design;

FIG. 2 is a left side view of the jewelry item shown in FIG. 1;

FIG. 3 is a right side view of the jewelry item shown in FIG. 1;

FIG. 4 is a front view of the jewelry item shown in FIG. 1; and,

FIG. 5 is a top view of the jewelry item shown in FIG. 1. The bottom of the jewelry item is plain and unornamented, and forms no part of the claimed design.

The broken line showing of shoe is for illustrative purposes only and forms no part of the claimed design.

1 Claim, 5 Drawing Sheets
